FURNACE STOKER

William P. Biddle, Jr., and Hugh W. Sanford, Jr.,
 Knoxville, Tenn., assignors to Hugh W. San-
 ford, Knoxville, Tenn.

Application December 2, 1941, Serial No. 421,356

17 Claims. (Cl. 110—109)

1

The invention relates generally to furnaces and has for an object to provide a novel form of stoker mounted on the door of a furnace and effective to mechanically feed solid fuel through said door and onto the fire bed in the furnace.

Furnace door mounted stoking equipments have been provided heretofore, but these have enjoyed only limited public approval because of various faults therein such as the complicated and expensive nature of their construction and operation, lack of proper control of the actual feeding of the solid fuel, and inability to handle large lumps or particles of fuel or foreign matter without jamming. It is the purpose of the present invention to provide an improved stoker structure in which all of these objectionable characteristics are avoided.

In its more detailed nature the invention resides in providing an improved form of furnace door mounted stoker comprising a housing rigidly mounted on the door, a hopper supported on the housing and having a gravity discharge throat extending downwardly into the housing, said door and housing having registering openings therein adjacent the throat and communicating with the interior of the furnace, a yieldable gate in part defining the portion of said throat nearest said openings and yieldable to permit passage of fuel lumps or large particles of foreign matter and to prevent excessive feeding of fine coal from the upper part of the hopper at the time that the yieldable gate is engaged by a coal lump, and a fuel feeding pusher reciprocable across the throat just beneath said gate and effective upon each forward stroke to deliver a charge of fuel through said openings into the furnace.

Another object of the invention is to provide a stoker structure of the character stated in which the pusher is oscillatably mounted and includes an arcuate plate portion the arc of which is struck from the center about which the pusher oscillates and which plate is effective to close the throat as the pusher moves forward, and in which the yieldable gate comprises a plurality of flexible spring steel fingers having their lower ends freely suspended to a point just short of the path of movement of said plate.

Another object of the invention is to provide a stoker structure of the character stated in which a fuel supporting plate is attached to the pusher in position for forming with the pusher a pocket or supporting shelf for receiving and supporting fuel when the pusher is retracted, and movable with the pusher, when the latter is projected to deliver a charge of fuel in the furnace, to a posi-

2

tion for aiding in the distribution of the charge of fuel over the fire bed in the furnace.

Another object of the invention is to provide in a stoker of the character stated a fuel supporting and distributing plate which is pivotally connected to the pusher and so engageable with fixed supporting means as to be positioned generally horizontally as a fuel supporting shelf beneath the yieldable gate when the pusher is retracted, and movable to a forward and downwardly inclined position extended in fuel distributing position into the interior of the furnace when the pusher is projected.

Another object of the invention is to provide in a stoker of the character stated power operated means for slowly oscillating the fuel feeding pusher and including a motor and crank and link connections for transmitting the rotary motion from the motor in the form of oscillatory motion to the pusher, said connections also including pawl and ratchet wheel devices.

Another object of the invention is to provide in a stoker of the character stated, movement transmitting connections including lost motion devices effective to enable adjustment of the stroke imparted to the pusher without altering the forward or fuel charging stroke limit of the pusher.

With the above and other objects in view that will hereinafter appear, the nature of the invention will be more fully understood by following the detailed description, the appended claims, and the several views illustrated in the accompanying drawings.

In the drawings:

35. Figure 1 is a vertical cross section of a furnace with the invention mounted on the door thereof, the normal, retracted position of the pusher being shown in dotted lines, and the fuel feeding and distributing position being illustrated in full lines.

40. Figure 2 is a vertical cross sectional view taken on the line 2—2 on Figure 1.

Figure 3 is an enlarged detail vertical cross sectional view taken on the line 3—3 on Figure 1.

45. Figure 4 is a detail vertical longitudinal sectional view taken on the line 4—4 on Figure 3.

In the exemplary disclosure of the invention herein illustrated the furnace 5 embodying the usual jacketed walls includes a fire bed supporting grate 6 which is accessible through a firing opening 7, said opening being normally closed by the usual hingedly mounted door 8. This furnace structure may be of any conventional form.

In the practical development of the invention 55 there is provided a housing or supporting struc-

ture 9 which is securely bolted or otherwise secured to the hinged door 8 and equipped with an opening registering with the firing opening 7 and an opening 10 formed in the door 8. A hopper 11 is supported on the housing 9 and includes a gravity discharge throat 12 which depends in the housing adjacent the registering openings 7 and 10.

The foremost wall of the hopper terminates, as at 13, a short distance below the top of the housing 9, and this wall is supplemented by a yieldable wall or gate structure generally designated 14 and composed of a rigidly mounted bar 15 and depending closely spaced spring steel fingers 16 which depend from said bar.

An oscillatable fuel feeder or pusher is pivotally supported, as at 17, in the housing beneath the discharge throat 12, and this pusher includes a flat front plate 18 and an arcuate top plate 19, the arc of the top plate being struck from the center about which the pusher oscillates. It will be observed by reference to Figure 1 of the drawings that the flexible fingers 16 comprising the yieldable wall 14 which defines the front portion of the throatway 12 extend downwardly to a point immediately above the path of travel of the arcuate plate 19.

A crank arm 20 is secured to and depends from the pusher 18, 19 and has a driving pin 21 projecting laterally from the lower end thereof. The driving pin 21 extends through a longitudinal slot 22 in the front end of a driving link 23, the effective length of the slot 22 being variable through the medium of a screw 24 adjustably mounted in a bearing 25 carried by the link. The purpose of this adjustment of the slot length will be described hereinafter. At its other end, the link 23 is connected to a crank pin 26 which projects laterally from a ratchet wheel 27 having a relatively large driving surface or periphery 28 and which is freely rotatable on a shaft or bearing pin 29 rigidly supported, as at 30, on the housing 9. It will be obvious that when rotation is imparted to the wheel 27, this rotary motion will be transmitted in the form of oscillatory motion to the pusher 18, 19 through the crank and link connections 26, 23, 21 and 20.

For imparting the desired rotary motion to the wheel 27 there is provided a driving arm 31 which is oscillatably mounted, as at 32, on the shaft 29, and this arm has a driving pawl 33 pivoted thereon, as at 34, in position for engaging in driving relation with the periphery 28 of the wheel 27. The pawl is disposed in the manner best illustrated in Figure 4 of the drawings so that it will drag freely over the wheel periphery when the arm is moved to the left, as viewed in Figures 1 and 4, and will engage in driving relation with said periphery when the arm is moved to the right thereby to impart rotation in a clockwise direction to said wheel. The arm 31 is slotted, as at 35, to adjustably receive a shoulder bolt 36 which is attached to the front end of a driving link 37. The other end of the link 37 is attached to a crank pin 38 which projects laterally from a driving disk 39 carried by the shaft 40 of a motor 41 rigidly supported, as at 42, upon the housing 9. It will be obvious that rotary motion of the disk 39 will be transmitted in the form of oscillatory movement to the arm 31 through the crank and link connections 38, 37 and 36.

A fuel supporting and feed distributing or spreading plate 43 is hingedly attached, as at 44, to the pusher plate 18, and this hingedly mounted plate is generally flat in shape and has its front

edge 45 curved slightly upwardly in the manner clearly illustrated in Figure 1 of the drawings. The normal or retracted position of the pusher 18, 19 is illustrated in dotted lines in Figure 1 of the drawings, and the forwardly projected or fuel feeding and distributing position of the pusher is illustrated in full lines in Figure 1. The plate 43 extends the full width of the pusher 18, 19 and is slightly less in width than the opening 10 which communicates between the discharge throat 12 and the interior of the furnace structure 5 through the firing door 7. When the pusher 18, 19 is in its normal, retracted position the plate 43 rests in generally horizontal position upon a cross rod 46 or other suitable supporting means mounted on the housing 9, and when the pusher 18, 19 is in its forwardly projected or fuel feeding and spreading position, the plate 43 is supported on a similar cross rod or supporting means 47 in the downwardly and forwardly inclined position illustrated in full lines in Figure 1 for effectively distributing the fed fuel charge over the fire bed.

By mounting the plate 43 in the manner stated and positioning the supporting elements 46, 47 in the manner hereinbefore described, when the pusher 18, 19 is in its retracted position illustrated in dotted lines in Figure 1, the front plate 18 and the plate 43 together form a pocket or fuel supporting shelf at the bottom of the fuel discharging throat 12, and the plate 43 lies in generally horizontal position beneath the lower extremities of the flexible fingers 16. When the pusher is moved to its forward position the plate 43 swings forwardly and downwardly, under control of the supporting elements 46, 47, to the fuel charge spreading position illustrated in full lines in Figure 1. It will also be observed by reference to the dotted line illustration in Figure 1 that when the pusher 18, 19 is in its normal, retracted position the plate 43 is disposed directly beneath and close to the upper limit of the firing opening 10 so as to effectively close that opening and guard against any possibility of fuel in the hopper throat 12 being ignited by radiant heat from the fire bed in the furnace.

By reason of the provision of the yieldable wall or gate 14 and the relation thereof to the hopper discharge throat 12 and the furnace fuel charging opening 10, the feeding of fuel charges can be accomplished without any danger of jamming of parts by reason of engagement of the pusher with coal lumps or any foreign particles contained in the fuel, movement of which is being obstructed by contact of unyielding surfaces. In other words, should the pusher move forwardly a charge of fresh fuel including one or more large lumps, and possibly a railroad spike, a stone or a similar bit of foreign matter, the wall or gate 14 or portions thereof are free to yield and permit passage of such lumps or particles without jamming of the parts and without free and uncontrolled outpouring of the fuel particles of lesser sizes at opposite sides of a jammed coal lump or other large particle.

It is desired that the pusher 18, 19 shall have a constant, that is, an unvarying forward stroke limit, this limit being the full line position illustrated in Figure 1 of the drawings. It is also desirable that the length of the stroke movement imparted to the pusher 18, 19 be variable so that the amount of each fuel charge fed into the furnace at each forward movement of the pusher may be varied. This is accomplished by adjustment of the screw 24 and the resultant variation

in the effective length of the slot 22 in the link 23. Adjustment of the effective length of this slot provides for a greater or lesser amount of lost motion in the pin and link connection 21, 23. It is to be understood that when the pusher 18, 19 is in its non-varying, forwardly projected position, the pin 21 will be engaged in the forward limit of the slot 22. When the link 23 moves forwardly to effect a retraction of the pusher, this retraction will not start until the variable lost motion has been taken up and the adjustable screw 24 engages the pin 21. By adjusting the position of the shoulder bolt 36 in the driving arm slot 35, the degree of the individual increments of movement imparted by the arm 31 to the wheel 27 can be varied.

It is to be understood that in a door feed stoker mechanism of the nature herein disclosed a satisfactory control can be effected with a simple thermostat. When the thermostat calls for heat the motor 41 is put into operation to impart step rotation to the wheel 27 and reciprocation to the pusher 18, 19 in the manner hereinbefore described, and the motor continues to operate until a sufficient amount of fresh fuel has been fed to the fire to build up heat sufficient to turn off the thermostat. It should also be understood that other conventional stoker controls can be used. In addition to the usual thermostat and bonnet control arrangement, a suitable mechanism may be employed which provides a certain feed timing during periods when the house and thermostat are overheated. The controls which have been mentioned are conventional, however, and since they in themselves form no part of the present invention, further detailed disclosure thereof is deemed unnecessary herein.

It will be obvious by reference to Figure 1 of the drawings that when the pusher 18, 19 is in the retracted position illustrated in dotted lines, the plate or shelf 43 will support the fuel in the hopper discharge throat 12 and effectively close the firing opening 10 so as to protect the fuel supply from radiant heat. As the pusher 18, 19 moves forwardly on a fuel charging and distributing stroke, the plate 43 will retain its generally horizontal position until a certain point is reached late in the forward movement of the pusher and the plate 43 hingedly mounted thereon. When this point is reached, the plate 43 will fall rapidly over the rod 48 and onto the rod 47 into the position illustrated in full lines in Figure 1 and in so doing will effectively distribute the fuel charge on the fire bed.

It is to be understood that the details of structure and arrangement of parts may be variously changed and modified without departing from the spirit and scope of the invention.

We claim:

1. A stoking apparatus for a furnace having a fire bed, and a firing door opening; a firing door, a housing carried by said door, a fuel hopper supported by the housing and having a gravity discharge throat normally open for delivery of fuel from said hopper and disposed in said housing, said door and housing having registering openings therein adjacent the throat and communicating with the interior of the furnace at an elevation above the fire bed so that fuel discharged through said throat and delivered through said openings will fall by gravity onto said fire bed, a yieldable uprightly disposed wall in part defining the portion of the normally open discharge throat nearest said openings and yieldable so as to be displaceable by fuel lumps or large particles of for-

ign matter to permit passage thereof toward said openings, and a fuel feeding pusher reciprocable across the throat close beneath said uprightly disposed yieldable wall and effective upon each forward stroke to deliver a charge of fuel from the throat through said openings and into the furnace.

2. A structure as defined in claim 1 in which the pusher is oscillatably mounted and includes a substantially arcuate plate portion the arc of which is struck approximately from the center about which the pusher oscillates and which plate is effective in one position of the pusher to close the throat, and in which the yieldable wall comprises a supporting bar and a plurality of closely spaced flexible fingers extending down close to but short of contact with said arcuate plate.

3. A structure as defined in claim 1 in which the pusher is oscillatably mounted and includes a substantially arcuate plate portion the arc of which is struck approximately from the center about which the pusher oscillates and which plate is effective in one position of the pusher to close the throat, and in which there is included a fuel supporting and distributing plate attached to the pusher, and means for supporting said supporting and distributing plate in position for forming with the pusher a pocket for receiving and supporting fuel when the pusher is retracted, said supporting and distributing plate being movable with the pusher, when the latter is projected to deliver a charge of fuel into the furnace, to a position for aiding in distributing the charge of fuel over the fire bed in the furnace.

4. A structure as defined in claim 1 in which the pusher is oscillatably mounted and includes a substantially arcuate plate portion the arc of which is struck approximately from the center about which the pusher oscillates and which plate is effective in one position of the pusher to close the throat, and in which there is included a fuel supporting and distributing plate pivotally attached to the pusher, and means movably supporting and guiding said supporting and distributing plate on the housing in such manner that it assumes a generally horizontal position beneath the yieldable wall for supporting fuel when the pusher is retracted and moves into a forwardly and downwardly inclined position as the pusher is moved to its projected position thereby to aid in distributing the charge of fuel over the fire bed in the furnace.

5. In a furnace wherein is provided a casing having a fire bed supporting means and an opening through which fuel can be fed onto the fire bed, stoking means including a hopper having a gravity discharge throat, means supporting said hopper in position for placing the throat adjacent said opening, a fuel feeding pusher, means reciprocably mounting said pusher in position for being reciprocable across the discharge throat for feeding fuel charges through said opening into the fire bed and effective in its forwardly projected position to close said throat, a motor, a crank driven by the motor, a crank disk, ratchet and pawl driving connections between the crank and the crank disk, and a link connected at one end to the crank disk and at its other end to the pusher.

6. In a furnace wherein is provided a casing having a fire bed supporting means and an opening through which fuel can be fed onto the fire bed, stoking means including a hopper having a gravity discharge throat, means supporting said hopper in position for placing the throat adjacent

said opening, a fuel feeding pusher, means reciprocably mounting said pusher in position for being reciprocable across the discharge throat for feeding fuel charges through said opening into the fire bed and effective in its forwardly projected position to close said throat, a motor, a crank driven by the motor, a crank disk, ratchet and pawl driving connections between the crank and the crank disk, and a link connected at one end to the crank disk and at its other end to the pusher, one of said link end connections constituting an adjustable lost motion connection.

7. In a furnace wherein is provided a casing having a fire bed supporting means and an opening through which fuel can be fed onto the fire bed, stoking means including a hopper having a gravity discharge throat, means supporting the hopper in position for placing the throat adjacent said opening, a fuel feeding pusher, means oscillatably mounting said pusher in position for being oscillated across said throat for feeding fuel through said opening, a driving motor including a driven shaft, a crank arm projecting from the pusher, driving crank means on said shaft, and power transmitting connections between the crank arm and said driving crank means whereby the rotary movement of the shaft will be transmitted in the form of oscillatory movement of the pusher.

8. In a furnace wherein is provided a casing having a fire bed supporting means and an opening through which fuel can be fed onto the fire bed, and a combination closure door and stoking means mountable and removable as a unit over said opening and comprising a hingedly mounted closure door, a housing carried by said door, a fuel hopper supported by the housing and having a gravity discharge throat normally open for delivery of fuel from said hopper and disposed in said housing, said door and housing having registering openings therein adjacent the throat and communicating with the interior of the furnace, a yieldable uprightly disposed wall in part defining the portion of the normally open discharge throat nearest said openings and yieldable so as to be displaceable by fuel lumps or large particles of foreign matter to permit passage thereof toward said openings, and a fuel feeding pusher reciprocable across the throat close beneath said uprightly disposed yieldable wall and effective upon each forward stroke to deliver a charge of fuel from the throat through said openings and into the furnace.

9. In a furnace wherein is provided a casing having a fire bed supporting means and an opening through which fuel can be fed onto the fire bed, and a combination closure door and stoking means mountable and removable as a unit over said opening and comprising a hingedly mounted closure door having an opening therein registering with said casing opening, a hopper having a gravity discharge throat disposed adjacent said registering openings, a fuel feeding pusher reciprocably mounted beneath said throat and including a plate portion effective in one position to close the throat, a fuel supporting and distributing plate attached to the pusher and fixedly mounted supporting means on which said supporting and distributing plate rests and effective to place said plate in a generally horizontal position for receiving and supporting fuel when the pusher is retracted and to place said plate in a forwardly and downwardly inclined position when the pusher is projected so as to deliver and dis-

tribute the supported fuel charge over the fire bed in the furnace.

10. In a furnace wherein is provided a casing having a fire bed supporting means and an opening through which fuel can be fed onto the fire bed, stoking means including a hopper having a gravity discharge throat, means supporting said hopper in position for placing said throat adjacent said opening, a fuel feeding pusher, means reciprocably mounting said pusher beneath said throat, said pusher including a plate portion effective in one position of the pusher to close the throat, a fuel supporting and distributing plate, and means for supporting said supporting and distributing plate in position for forming with the pusher a pocket for receiving and supporting fuel when the pusher is retracted, said supporting and distributing plate being attached to the pusher and movable therewith when the pusher is projected to deliver a charge of fuel into the furnace to a position for aiding in the distribution of the charge of fuel over the fire bed in the furnace.

11. In a furnace wherein is provided a casing having a fire bed supporting means and an opening through which fuel can be fed onto the fire bed, stoking means including a hopper having a gravity discharge throat, means supporting said hopper in position for placing said throat adjacent said opening, a fuel feeding pusher, means reciprocably mounting said pusher in generally horizontal position beneath said throat, said pusher including a plate portion effective in one position of the pusher to close the throat, a fuel supporting and distributing plate, and means for supporting said supporting and distributing plate in position for forming with the pusher a pocket for receiving and supporting fuel when the pusher is retracted, said supporting and distributing plate being attached to the pusher and movable therewith when the pusher is projected to deliver a charge of fuel into the furnace to a position for aiding in the distribution of the charge of fuel over the fire bed in the furnace, said pusher also including a front plate disposed generally uprightly and connected at the foremost edge portion of the pusher plate portion, and said fuel supporting and distributing plate having its place of attachment with the pusher at a point on said front plate spaced downwardly from the connection of said front plate with the arcuate plate.

12. In a furnace wherein is provided a casing having a fire bed supporting means and an opening through which fuel can be fed onto the fire bed, stoking means including a hopper having a gravity discharge throat, means supporting said hopper in position for placing said throat adjacent said opening, a fuel feeding pusher means oscillatably mounting said pusher beneath said throat, said pusher including a substantially arcuate plate portion the arc of which is struck approximately from the center about which the pusher oscillates and which substantially arcuate plate is effective in one position to close the throat, a fuel supporting and distributing plate, and means for supporting said supporting and distributing plate in position for forming with the pusher a pocket for receiving and supporting fuel when the pusher is retracted said supporting and distributing plate being hingedly attached to the pusher and movable therewith when the pusher is projected to deliver a charge of fuel into the furnace to a position for aiding in the distribution of the charge of fuel over the fire bed in the furnace, said pusher also including a

front plate connected at the foremost edge portion of the substantially arcuate plate and projecting substantially radially with respect to the center about which the pusher oscillates, and said fuel supporting and distributing plate having its hinge attachment with the pusher at a point on said front plate spaced downwardly from the connection of said front plate with the substantially arcuate plate, and said distributing plate supporting means being disposed to support the distributing plate in such manner that it will assume a generally horizontal position beneath the throat when the pusher is retracted and will move into a forwardly and downwardly inclined position over said supporting and guiding means as the pusher is moved to its projected position.

13. In a furnace wherein is provided a casing having a fire bed supporting means and an opening through which fuel can be fed onto the fire bed, stoking means including a hopper having a gravity discharge throat, means supporting said hopper in position for placing the throat adjacent said opening, a fuel feeding pusher, means reciprocably mounting said pusher beneath said throat, said pusher including a plate portion effective in one position to close the throat, a fuel supporting and distributing plate attached to the pusher, and fixedly mounted supporting means on which said supporting and distributing plate rests and effective to place said plate in a generally horizontal position for receiving and supporting fuel when the pusher is retracted and to place said plate in a forwardly and downwardly inclined position when the pusher is projected so as to deliver and distribute the supported fuel charge over the fire bed in the furnace.

14. A structure as defined in claim 10 in which the fuel supporting and distributing plate is

hingedly attached to the pusher, and in which the supporting and distributing plate supporting means is disposed close beneath the plate hinge attachment when the pusher is projected so that the fuel supporting and distributing plate will fall rather rapidly to its forwardly and downwardly inclined position just as the pusher approaches its projected position thereby to facilitate distribution of each fuel charge over the fire bed in the furnace.

15. A structure as defined in claim 10 in which there is included means for so positioning the fuel supporting and distributing plate when said plate is retracted and in the opening through which fuel can be fed onto the fire bed that it closes said opening and protects fuel in the hopper discharge throat from the direct action of radiant heat from said fire bed.

16. A structure as defined in claim 7 in which said power transmitting connections include a ratchet wheel having a crank pin projecting therefrom, ratchet and pawl driving connections between the shaft borne crank and said ratchet wheel, and a link connecting the crank pin of the ratchet wheel with the pusher crank.

17. A structure as defined in claim 7 in which said power transmitting connections include a ratchet wheel having a crank pin projecting therefrom, ratchet and pawl driving connections between the shaft borne crank and said ratchet wheel, and a link connected at one end to the crank pin of the ratchet wheel and at its other end to the pusher crank, one said link end connection constituting an adjustable lost motion connection.
